[57] **CLAIM**

The ornamental design for a combined waste receptacle and dispenser, as shown and described.

DESCRIPTION

FIG. 1 is a perspective view of a combined waste receptacle and dispenser showing my new invention;
FIG. 2 is a top plan view thereof;
FIG. 3 is a front elevational view thereof;
FIG. 4 is a side elevational view taken from the right of FIG. 3, the opposed side being a mirror image thereof;
FIG. 5 is a bottom plan view thereof; and,
FIG. 6 is a rear elevational view thereof.
